(57) **CLAIM**

I claim the ornamental design for a magnifying device, as shown and described.

DESCRIPTION

FIG. 1 is a perspective view of a magnifying device showing my new design in a first configuration, as viewed from the top and one side.

FIG. 2 is a front elevation view of the magnifying device of FIG. 1 in the first configuration.

FIG. 3 is a back elevation view of the magnifying device of FIG. 1 in the first configuration.

FIG. 4 is a side elevation view of the magnifying device of FIG. 1 in the first configuration, the opposite side elevation view being a mirror image thereof.

FIG. 5 is a top plan view of the magnifying device of FIG. 1 in the first configuration.

FIG. 6 is a bottom plan view of the magnifying device of FIG. 1 in the first configuration; and,

FIG. 7 is a perspective view of the magnifying device of FIG. 1 in a second configuration, as viewed from the top and one side.

The details shown in broken lines illustrate portions of the magnifying device that form no part of the claimed design.
